SLASHING MECHANISM FOR RIB APPLYING MACHINES

Andrew R. Ridderstrom, Nahant, Mass., assignor to Prime Manufacturing Company, Lynn, Mass., a corporation of Massachusetts

Application March 18, 1952, Serial No. 277,153

5 **5 Claims. (Cl. 12—20)**

This invention comprises a new and improved slashing or pinking mechanism for rib applying machines such as those employed for adhesively attaching a sewing rib to a flat insole blank.

In applying to an insole blank a sewing rib that is secured by an adhesive tape, it has been found that the tape has a tendency to curl up or away from the underlying surface of the insole. This tendency is so strong about the convex curvature of the toe that in the case of laminated insoles the laminations may be actually separated from each other by the pull of the tape thus introducing a serious defect into the shoemaking process.

The object of the present invention is to correct this situation and to provide an improved slashing or pinking knife that will be effective as stripping is laid to interrupt the continuity of the tape, thus eliminating tension in its convex margin and insuring a stable flat condition.

The salient feature of the invention is a slashing knife located in the feed foot of a rib applying machine in such a manner that as the adhesive tape portion of the composite rib is progressively pressed upon the insole blank, its margin will be slashed and there will be no initial tension tending to disturb the flat position of the tape.

Preferably and as herein shown, the body of the feed foot has a substantially flat work-engaging surface intersected by a rib-receiving groove, and the slashing knife is mounted in the body portion of the foot with its cutting edge projecting beyond its work-engaging face and located wholly on one side of the rib-receiving groove.

In a preferred form of the invention the foot is provided with a circular passage opening downwardly through its work-engaging face and a cylindrical knife is located in this passage and backed up by an adjusting screw located tangentially behind the inner end of the knife. This construction is advantageously compact. It affords a convenient, accurate and secure means of adjusting and holding the knife as well as convenient provision for removal of the knife for sharpening or replacement.

These and other features of the invention will be best understood and appreciated from the following description of a preferred embodiment thereof, selected for purposes of illustration and shown in the accompanying drawings in which:

Fig. 1 is a view in elevation showing so much of the rib-applying machine as is necessary to understand the slashing knife mechanism,

Fig. 2 is a fragmentary view on an enlarged scale showing the slashed ribbing as applied to the portion of an insole,

Figs. 3 and 5 are views in elevation of the presser foot as seen from opposite sides,

Fig. 4 is a view of the presser foot in end elevation showing its relation to the insole, and

Fig. 6 is a fragmentary view showing the path of movement of the presser foot.

In Fig. 2 is illustrated one example of the work performed by the slashing mechanism of this invention. In this instance a sewing rib is applied to a flat insole 10. The rib comprises an upright core 11 which is enclosed in an adhesive tape 12. The tape is turned laterally in both directions from the core and presents an outturned portion which lies flush with the marginal edge of the sole 10 and a somewhat wider inturned portion which lies on the inner side of the core 11. The tape is adhesively coated and adheres to the core 11 and to the surface 10 of the insole which has been previously coated with cement. In rounding the toe portion of the insole

2

pleats 13 are formed in the inturned portion of the adhesive tape and slashes 14 are formed at regular intervals in its outturned portion. These are formed by the mechanism of the present invention which will now be described.

In Fig. 1 sufficient of the machine of my prior Patent No. 2,142,332 is shown for a complete understanding of the present invention. In the frame 16 is journaled a freely rotatable work-supporting roll 17 and a pair of driven shafts 18 and 19 on both of which is formed a pair of eccentrics arranged to operate arms 20 and 21 carrying the feed feet. The eccentrics are so timed as to move the arms alternately in a tape feeding and pressing path of the character shown in dotted lines in Fig. 6, and so impart longitudinal feeding movement to the sole and tape beneath them.

A guide foot 22 for the composite stripping is adjustably fastened to a bracket member 23 pivotally mounted to rock about a pivot 24 and controlled in its position through a link 25 connected to a rocker member 26 pivotally mounted upon a shaft 27 in the machine frame and operated through a treadle lever 28. Cut-off mechanism 29 is arranged to swing bodily about the shaft 24 and is brought into operative or inoperative position alternately with the guide foot 22 under the control of the treadle rod 28. The parts of the machine thus far described form no part of the present invention.

The arm 21 carries the feed foot 30 illustrated in Figs. 3-5. The body of the feed foot has a substantially flat lower work-engaging face which is intersected by a rib-receiving groove 31 that longitudinally divides the work-engaging foot into an inner portion 32 and an outer knurled portion 33. The insole and ribbing material are presented to the feed feet upon the roll 17 in such a manner that the inner portion 32 of the feed foot engages the inturned portion of the adhesive tape 12 while the outer portion 33 of the feed foot engages that portion of the tape which lies outside the rib and is laid substantially flush with the outer periphery of the insole 10. The upstanding rib passes freely through the longitudinal groove 31. The arm 20 carries a feed foot which may be similar in shape to the feed foot 30, and it will be understood that these two feet are operated alternately so that one is in feeding engagement with the work while the other is being lifted and returned by the path shown in Fig. 6 to engagement with the work.

The outer portion of the feed foot 30 is herein shown as provided with a circular or cylindrical slot 34 opening at its forward end through the knurled work-engaging face of the outer portion 33 of the feed foot and at its rear end through the body of the foot which is shouldered or stepped as shown in Figs. 3 and 5. The slot 34 is about 160° in length and opens continuously and laterally through the outer face of the portion 33 of the feed foot.

The slashing knife 35 which has the shape of a cylindrical segment fitting the groove 34 is received within that groove and is backed up at its rear end by an abutment screw 36 that is threaded into the body of the foot, tangentially disposed with respect to the knife and arranged to be held in position by a lock nut. The knife 35 is set by adjustment of this screw so that its sharpened blade protrudes downwardly beyond the knurled work-engaging face of the feed foot and at right angles to the rib-receiving groove 31. As shown in Fig. 4, its straight sharpened edge is inclined at an angle of approximately 5° to the horizontal to impart a shearing effect to its cutting action. The knife 35 is retained in the circular slot 34 by the head of a retaining screw 37 which is threaded into the side wall of the foot.

It will be understood that the slashing knife 35 is set in the foot so that each time the foot engages and presses the tape laid outside the rib, the knife will form one of the slashed cuts 14 shown in Fig. 2. The depth of the cut is regulated by the distance by which the knife edge protrudes beyond the knurled face of the outer portion 33 of the feed foot. The optimum adjustment is that in which the edge of the knife slashes completely through the adhesive tape but does not enter the material of the insole 10 and, as already explained, the effect of the slashes is to eliminate deforming tension from the slashed

portion of the tape so that it will lie naturally in stable flat condition.

Having thus disclosed my invention and described in detail a preferred embodiment thereof, I claim as new and desire to secure by Letters Patent:

1. A feed foot for imparting longitudinal feeding movement to a sole in a rib-applying machine, comprising a body portion having a substantially flat work-engaging face intersected by a rib-receiving groove, and a cylindrical slashing knife mounted in the said body portion and having a straight cutting edge projecting beyond the work-engaging face of the feed foot, located wholly on one side of the rib-receiving groove and disposed at substantially right angles thereto.

2. In a rib-applying machine, a feed foot for imparting longitudinal feeding movement to a sole and having two portions separated by a longitudinal rib-receiving groove, one of said portions having a curved passage therein, a curved knife adjustably contained in said passage and having a straight protruding cutting edge disposed at substantially right angles to said groove, an abutment screw in the feed foot engaging the rear unsharpened edge of the curved knife, and means for retaining the knife against lateral displacement in its passage.

3. In a rib-applying machine, a pair of feed feet operating alternately to impart longitudinal feeding movement to a sole, means for operating them alternately to engage and advance simultaneously an insole and a sewing rib strip including an adhesive tape, one of said feet having a longitudinally grooved work-engaging face, and a cylindrical slashing knife adjustably mounted in said foot in that portion thereof which engages the adhesive tape laid about the convex toe end of the insole and having a straight cutting edge disposed at substantially right angles to the groove of the feed foot.

4. In a rib-applying machine, a feed foot having a grooved work-engaging face, a cylindrical passage in the foot at least 90° in length and opening downwardly through the work-engaging face thereof, a cylindrical knife located in said passage and having a straight transversely inclined cutting edge protruding from the passage, and an adjusting screw located tangentially behind the inner end of the knife in the feed foot.
5. In a rib-applying machine, a foot having a flat work-engaging face for pressing an adhesive tape progressively upon an insole and a side face disposed at approximately right angles thereto, the foot having a semicircular passage leading at one end to the work-engaging face and opening transversely through the side face of the foot, an adjusting screw in the foot tangentially disposed with respect to the passage, a cylindrical knife in the passage having a straight cutting edge disposed approximately parallel to its axis of curvature, and a clamping screw threaded into the side face of the foot adjacent to the semicircular passage for holding the knife fixed in adjusted position.
